(57) **CLAIM**

The ornamental design for a double-data-rate SDRAM card, as shown and described.

DESCRIPTION

FIG. 1 is a front perspective view of a double-data-rate SDRAM card in accordance with my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear perspective view thereof; and

FIG. 9 is an enlarged view of IX part in FIG. 8; and,

FIG. 10 is an enlarged view of X part in FIG. 8.

The broken lines depict portions of the double-data-rate SDRAM card in which the design is embodied that form no part of the claimed design.
